DESIGN FOR AN OPERATING LEVER FOR TANK CLOSURES

Ward M. Gadberry, Kansas City, Mo., assignor to
Andrew A. Kramer, Kansas City, Mo.

Application August 24, 1935, Serial No. 58,285

Term of patent 14 years

To all whom it may concern:

Be it known that I, Ward M. Gadberry, a citizen of the United States, residing at Kansas City, in the county of Jackson and State of Missouri, have invented a new, original, and ornamental Design for an Operating Lever for Tank Closures, of which the following is a specification, reference being had to the accompanying drawing, forming a part thereof.

The figure is a perspective view of my new design.

I claim:

The ornamental design for an operating lever for tank closures substantially as shown.

In testimony whereof I hereunto subscribe my name this 12th day of August, 1935.

WARD M. GADBERRY.
